UNITED STATES PATENT OFFICE.

MARY VANDERPOOL HAYES, OF NEWARK, NEW JERSEY.

EVAPORATOR FOR HOT-AIR REGISTERS.

SPECIFICATION forming part of Letters Patent No. 738,438, dated September 8, 1903.

Application filed May 22, 1903. Serial No. 158,228. (No model.)

To all whom it may concern:

Be it known that I, MARY VANDERPOOL HAYES, a citizen of the United States, residing at Newark, in the county of Essex and State of New Jersey, have invented a certain new and useful Improvement in Evaporators for Hot-Air Registers, of which the following is a specification.

It is well known that in the use of heaters for buildings, and particularly in living apartments, the atmosphere becomes very dry, which is objectionable for various well-known reasons. It has been attempted to overcome this difficulty by providing heating-stoves with evaporating pans or cups adapted to contain water which is evaporated by the heat of the stove to maintain a certain degree of moisture in the atmosphere. While these devices accomplished to a certain extent the object for which they were intended, they are not entirely practical for the reason that the evaporating-surface is of too limited an area and for the reason that the water is not sufficiently heated to produce the proper degree of evaporation.

The object of my invention is to provide a device which will give the desired degree of evaporation and which may be employed with heating-stoves of different designs, and more particularly one which may be employed with hot-air registers.

In carrying my invention into effect I employ a cloth of any suitable texture, the ends of which are immersed in water contained in a suitable reservoir and which cloth will remain moist, due to absorption, so long as water remains in the reservoir. The reservoir and the means for supporting the cloth may be of any suitable form; but I prefer to employ two reservoirs provided, preferably, with means for holding them in an adjusted position relative to each other and to the heater or hot-air register. The supporting-frames for the cloth are also preferably adjustable in height. I also provide a pair of rolls in each reservoir for holding and feeding the cloth from one reservoir to the other, although the latter feature is not essential.

My invention is illustrated in the accompanying drawings, in which—

Figure 1 is a plan view of the preferred form of my device applied to a hot-air regis-

ter, the cloth being omitted to permit illustration of the other parts; and Fig. 2 is a vertical section on the line xx of Fig. 1 with the cloth in position.

Referring to the drawings, A represents the usual form of hot-air register, B and B' two reservoirs containing water or other suitable fluid, and C the evaporating-cloth. Each reservoir is provided with a pair of hook-shaped arms b, which are adapted to project through the grating of the top plate of register A. Each reservoir is provided with a solid arm b' and a tubular arm b², which are adapted to telescope with the corresponding arms of the opposite reservoir, the tubular arms being provided with set-screws for binding said arms together, and thereby securing the reservoirs in the adjusted position.

From the foregoing it will be understood that the hook-shaped arms b of the two reservoirs may be inserted into openings of register A at any desired point, and the telescoping arms may be adjusted so as to hold the reservoirs rigidly in position and at the same time prevent their tilting toward each other. Each of the arms b' and b² is provided with a collar having a socket d, adapted to receive the downwardly-projecting ends of wire frames D and D', which support the cloth C. These frames, as will be seen, are adjustable in sockets d, so that the cloth may be held at any desired elevation within limits. The ends of the cloth are passed between two pairs of rollers E and E', each pair being geared together and one roll of each pair being provided with a knob or handle for rotating the same. In order to readily feed the cloth and to hold the same in position without clamping it between the rolls, which would retard absorption, I provide the rolls with a series of projections e, which enter the cloth. Feeding-rolls E' are journaled in a pair of slotted plates e², secured to the inner side of reservoir B' in any suitable manner, the ends of the slots, as shown in Fig. 2, limiting the space between the rolls. Feeding-rolls E in reservoir B are similarly supported in slotted plates e'; but one plate in each reservoir is provided with an additional vertical slot e³ to permit the removal of one roll, if necessary, to facilitate the insertion of the cloth. To prevent the outer roll of each pair

becoming displaced, I provide pivoted spring-pressed fingers e^4 , which hold the outer roll in the desired position relative to the inner roll. By reference to the drawings it will be observed that the outer roll of each pair may be readily removed from the reservoir by pressing it backward against the fingers e^4 until its shaft is in alignment with the vertical slot e^8 , when the roll may be raised without interference. To return this roll to its position, it is only necessary to insert the ends of the shaft in slots e^8 and press the roll downward until the ends of its shaft snaps into position in the horizontal slots.

15 While ordinarily the cloth might remain in a moist condition if of good absorbent material, it may sometimes happen that the evaporation of the water is more rapid at one time than at other times, and it may become necessary to shift the cloth frequently, so as to present a thoroughly-moistened area to the column of hot air from the register. It is for this purpose that the feeding arrangement is provided, and it will be seen that as the cloth 20 is fed from one reservoir toward the other a thoroughly-moistened area may be brought in position, while the dry portion will be immersed in the opposite reservoir.

A single roll may be employed in each reservoir and the ends of the cloth wound thereon, so that it may be fed back and forth; but with such an arrangement it would be necessary to immerse the rolls in the water and make necessary a packing for the shafts to 30 prevent leakage. It will also be understood that the frames D and D' may be provided with teeth to hold the cloth and the rolls entirely dispensed with; but with such an arrangement to adjust the cloth it would be necessary to disengage it from the teeth on 35 both frames and readjust both ends, whereas with the feed-rolls the cloth may be moved in either direction by simply rotating one of the rolls.

45 It is evident that the cloth may be of any desired width relative to the length of the rolls and that in order to regulate the size of the evaporating area relative to that of the register one or more strips of cloth, each narrower than the lengths of the rolls, may be

used, or for rapid and easy adjustment the cloth may be gathered in plaits. This latter can be quickly and easily done by forcing the outer rolls outward and adjusting the cloth by hand. On the rolls being replaced the 53 projections thereon will hold the cloth in such position even when the rolls are rotated.

What I claim as my invention, and desire to secure by Letters Patent of the United States, is—

1. In a liquid-evaporator, the combination with a reservoir for containing liquid, a pair of feed-rolls journaled in the ends of said reservoir, an absorbent fabric partially immersed in said liquid and passing between said rolls 65 and means for exposing a portion of said fabric to a current of warm air.

2. In a liquid-evaporator, the combination of a pair of reservoirs for containing liquid, a pair of feed-rolls journaled in the ends of 70 each of said reservoirs, adjusting-rods connecting the adjacent walls of said reservoirs, supporting-frames projecting above said reservoirs, an absorbent fabric having its ends immersed in the liquid and passed between 75 said rolls and over and stretched between said frames.

3. In a water-evaporator, the combination of a pair of water-reservoirs, a hot-air register, said reservoirs located at the opposite 80 ends of said register, a pair of feed-rolls in each reservoir, an absorbent fabric having its ends passed between the pairs of feed-rolls and its intermediate portion stretched between said reservoirs and in the current of 85 hot air from the register.

4. In a liquid-evaporator, the combination of a pair of liquid-reservoirs, a hot-air register, hooks on one side of each of said reservoirs, said hooks being inserted in the spaces 90 in the upper part of said register and adjustable rods on the side of each of said reservoirs for spacing the same and an evaporating-cloth stretched between said reservoirs.

This specification signed and witnessed this 95 20th day of May, 1903.

MARY VANDERPOOL HAYES.
